UNITED STATES PATENT OFFICE.

JOHN WILLIAMS, OF JERSEY CITY, NEW JERSEY, AND EDWARD J. FROST
AND WILLIAM DAWSON, OF PHILADELPHIA, PENNSYLVANIA.

LAMP FIXTURE AND VENTILATOR FOR RAILWAY-CARS.

SPECIFICATION forming part of Letters Patent No. 400,984, dated April 9, 1889.

Application filed June 5, 1885. Serial No. 167,774. (No model.)

To all whom it may concern:

Be it known that we, JOHN WILLIAMS, of Jersey City, in the State of New Jersey, and EDWARD J. FROST and WILLIAM DAWSON, both of Philadelphia, in the State of Pennsylvania, have invented certain new and useful Improvements in Lamp Fixtures and Ventilators for Railway-Cars.

The following is a specification of our said improvements, reference being had to the accompanying drawings, wherein—

Figure 1 is an exterior side view of the lamp-fixtures; Fig. 2, a vertical central section through the same; Fig. 3, a vertical central section through the lamp fixture and ventilator on a plane at right angles to that of the section in Fig. 2. Fig. 4 is a horizontal section through the chimney-holding device on the line $x x$ of Fig. 1. Figs. 5 and 6 are detail views, on an enlarged scale, of a portion of the shade-holder and its hinge.

The objects of our invention are to provide a lamp for railroad use which shall be strong and durable, protected against disturbances from accidental currents of air, readily accessible for cleaning purposes, sightly in appearance, and which shall combine in itself the best method of supplying air for combustion, and at the same time of carrying off the products of combustion and ventilating the car.

In the drawings, R represents the roof of the car, from which the lamp is suspended by means of arms A, which may be of any ornamental form. Through one of these arms the gas to be burned is admitted and is carried down by means of a curved extension, a, to the burner B. This may be the ordinary Argand burner with the usual chimney, C. Within the lower ends of the arms A is attached a horizontal ring or band, G, of metal, of sufficient width to conceal the joints of the upper and lower portions of the lamp-shades, as hereinafter described. To this ring is hinged at d a second ring, E, preferably bevelled, as shown, on its lower surface, and provided with an interior flange or rim, e, secured to it by means of screws. A bell-glass or inverted dome, D, is secured by means of its outwardly-projecting rim between the flange e and the ring E, and is thus held in

position, so as to completely inclose the bottom of the lamp. Opposite to the hinge d of the ring E is an ordinary spring-latch, g, mounted in one of the arms A and projecting through the adjacent portion of the ring G into an opening formed in the upwardly-projecting piece S upon the ring E. The hinge d is provided (see Figs. 5 and 6) with a coiled spring, c, so arranged as to be wound up or tightened when the bell-glass D swings downward upon the hinge. This spring c prevents the bell-glass D from swinging too far backward and striking either the arm A or being broken by a too sudden stoppage upon its hinge. A porcelain shade, F, rests upon the top of the ring G and extends downward within the same, preferably to a point just above the edge of the bell-glass D. Thus the lamp is completely inclosed by glass and porcelain, which do not become tarnished and are, moreover, easily cleaned; but the joint between them, which otherwise would be unsightly, is concealed from below by means of the ring G and E. Set-screws b are provided to properly secure the shade F from displacement. Around the top of the opening in this shade F is a loosely-fitting metallic ring, f, to one side of which a segment, h, of brass is secured by means of screws, 80 as shown, said piece h extending about half-way around the ring. Upon the opposite side of the ring f is a set-screw, i, to which is attached a second segment, i, also of brass, which, however, is not secured to the ring f, 85 and can be clamped against the shade F by means of the set-screw I. The upper portion of the ring f is provided with inwardly-projecting tongues, t, between which, as well as through which, are openings k, as shown clearly in Fig. 1. The object of these tongues t is to support the second chimney-piece, H, which is provided with a rim or flange, l, adapted to rest upon the tips of the tongue, as shown. The purpose of the openings k in said tongues 90 will be explained hereinafter. To the outwardly-flaring lower end of this chimney H is attached a light ring, w, which is provided with several downwardly-depending fingers, m, joined together at their lower ends by 100 means of a second light ring, p, and having curved springs q, arranged within them, so

as to bear lightly against the upper portion of the glass lamp-chimney C. The whole structure of the internal chimneys, C and H, is thus held firmly together, and also secured to the lamp-shade F in such a way as to permit ready removal of the different parts, and as also to avoid a too great rigidity in the attachments between glass or porcelain and metal.

10 Above the lamp and within the roof of the car are mounted the ventilator-chimneys L and M, having an open space between them. Near the top of the outer chimney, M, are a number of openings, u, around which is a ring or band, N, with a free space between it and the exterior of M, and over the whole of this is a slightly conical top or roof, o, having a downwardly-depending rim, P. Beneath that portion of the roof o which is immediately over the inner chimney, L, is a metallic shield, r. When the lamp is burning, the air necessary to supply combustion is practically all admitted through the openings k through the tongues t, since very little can enter around or between the arms of the shade F and bell-glass D. The entering air is therefore heated by contact with the metallic tongues t, and also with the second chimney, H, and is thus supplied to the flame in a condition highly 25 advantageous for producing the best combustion.

30 The products of combustion pass out through the central chimney, L, and thence by means of the openings u to the outer air.

35 At the same time the heating of the two chimneys L and M produces an upward current of air from the car through the opening space between said chimneys, and hence tends to ventilate the car. Said open space also prevents the overheating of the car-roof by contact with the chimney L.

40 The lamp is so completely inclosed as to be entirely inaccessible to the most violent currents of air within the car, and at the same time the white reflecting surface of the porcelain shade above and the practically unobstructed bell-glass D below illuminate the car in the most desirable manner and without casting objectionable shades either above or 45 below. The protection of the double chimney L and M on the outside we have found amply sufficient to guard against any disturbances of the light by blasts of air from without.

The other advantages, which relate to the 55 cleaning or removal of the lamp or portions thereof, will be obvious, and hence are not further particularized.

Having thus described our invention, we claim—

1. The combination, with the burner and its chimney, of the inclosing bell-glass and the inclosing dome-shaped reflecting-shade, the edges of which meet together, so as to form an unobstructed space around said 65 burner and chimney, the supporting ring or frame surrounding the joint of said shade and glass, and a perforated support in the upper contracted open end of said shade surrounding and supporting the upper end of said 70 chimney and admitting air to feed the burner, substantially as described.

2. The combination, with the burner and its chimney, of the dome-shaped reflecting-shade having a contracted upper open end, 75 the perforated clamp-ring fitted to said shade and securely supporting a separable chimney-piece therein, and a spring-clamp connection of said chimney-piece supporting the upper end of said chimney, substantially as de- 80 scribed.

3. The chimney-piece supporting-ring consisting of the annular ring fitted around the reflecting-shade, the perforated extension or fingers fitted to support said chimney-piece, 85 and the movable clamp-segment of said supporting-ring and its adjusting clamp-screw I, substantially as described.

4. The combination of the chimney, the separable chimney-piece fitted above it, and the 90 double-ring clamp-connection between said chimney and chimney-piece, consisting of a ring secured to the lower end of said chimney-piece and connected by fingers with a second ring grasping the upper end of said chimney 95 by interposed springs, substantially as described.
